UNITED STATES PATENT OFFICE

165,797

MERCHANDISE DISPLAY CASE

Maurice L. Shanahan, Los Angeles, Calif.

Application September 13, 1951, Serial No. 16,587

Term of patent 14 years

(Cl. D80—11)

To all whom it may concern:

Be it known that I, Maurice L. Shanahan, a citizen of the United States, residing at Los Angeles, in the county of Los Angeles and State of California, have invented a new, original, and ornamental Design for a Merchandise Display Case, of which the following is a specification, reference being made to the accompanying drawing, forming a part thereof.

Figure 1 is a perspective view of a merchandise display case showing my new design;

and

Figure 7 is a fragmental longitudinal sectional view.

I claim:

The ornamental design for a merchandise display case, as shown.

MAURICE L. SHANAHAN.
